UNITED STATES PATENT OFFICE.

EDWARD J. MURPHY, OF BARBERTON, OHIO.

LIGHTING DEVICE.

1,103,611.

Specification of Letters Patent. Patented July 14, 1914.

Application filed September 24, 1912. Serial No. 722,020.

To all whom it may concern:

Be it known that I, EDWARD J. MURPHY, a citizen of the United States, residing at No. 123 Ford avenue, Barberton, Ohio, have invented certain new and useful Improvements in Lighting Devices, of which the following is a specification.

This invention relates to improvements in lighting devices.

10 My improvements relate particularly to lighting devices of the class or type in which sparks are produced by the rubbing of a pyrophoric or other suitable material across an abrader.

15 The main object of this invention is to provide a lighting device which is simple in structure and operation and very durable in use, the parts subject to wear being readily renewed.

20 Further objects, and objects relating to structural details, will definitely appear from the detailed description to follow.

I accomplish the objects of my invention by the devices and means described in the 25 following specification. The invention is clearly defined and pointed out in the claims.

A structure which is a preferred embodiment of my invention is clearly illustrated in the accompanying drawing forming a part 30 of this specification, in which:

Figure I is a detail side elevation of a structure embodying the features of my invention, the member 1 being indicated in open position by dotted lines. Fig. II is a 35 side elevation looking from left of Fig. I. Fig. III is a detail view partially in section in line corresponding to line 3—3 of Fig. II. Fig. IV is a detail section on line corresponding to line 4—4 of Fig. II. Fig. V is a detail view partially in section on line 40 corresponding to line 5—5 of Fig. II.

In the drawing similar reference characters refer to similar parts throughout the several views, and the sectional views are 45 taken looking in the direction of the little arrows at the ends of the section lines.

Referring to the drawing I provide a pair of pivoted members as 1 and 2 pivotally connected at 3. The members 1 and 2 are provided with handles 4 and 4'. An A-shaped spring 5 is arranged between the members 1 and 2 below the pivot 3, one arm of the spring resting in the member 2 which is formed of sheet metal U-shaped in cross 55 section the other arm of the spring resting

against the member 1 and being held in position by the handle 4. See Fig. V. The member 1 is notched at 15 to receive the lug 16 at the end of the spring. The member 2 is turned laterally at its outer end to provide a supporting arm 7 for the abrader. The arm 7 is provided with a longitudinal slot 8. The abrader 10 is removably supported by the pin 9 arranged through the member 2 and the ear 7'. The pin is secured by the cotter pin 9'. The abrader 10 is cylindrical and crowned with a file like surface. The abrader 10 is held normally against rotation between the side of member 2 and the ear 7'. 70

The member 1 is provided with a lateral offset 1' embracing the arm 7. The member 1 is preferably a rod and adapted to close into the member 2. The member 2 is provided with ears 3' for the pivot 3, the member 1 being arranged between the ears as shown. The member 1 is provided with a holder 11, having a bore-like socket 11' therein. The holder 11 is mounted so as to overhang the arm 7. A block 12 of pyrophoric or other suitable material is arranged in the holder socket with its end through the slot 8 in the arm 7. The block is supported by the coiled spring 13 arranged in the socket 11', the spring being supported by 85 the follower 14 threaded into the outer end of the socket.

The handles 4 and 4' serve as stops to limit the opening movement. By removing the handle 4 the members can be swung so that the holder 11 clears the arm 7 to permit the insertion or removal of the block 12. By this simple arrangement the blocks can be renewed quickly and easily and at the same time are effectively supported. The 90 handle 4' is preferably adapted as a holder for a supply of the blocks 12, the same being provided with removable cap 17. The abrader 10 can be renewed if desired, but that is required only after long use as it 100 may be adjusted so that its entire surface can be utilized. 95

My improved lighting device is simple in structure and operation. Owing to the block 12 being held in contact with the abrader by means of the spring 13 a good contact is maintained until the block is worn out. By adjusting the follower 14 the proper amount of friction pressure is secured. 105

Having thus described my invention, what 110

I claim is new and desire to secure by Letters Patent is:

1. An igniting device comprising a pair of pivoted members, one of the members being turned laterally and inwardly to provide an abrader supporting arm with an ear at its outer end, said arm being longitudinally slotted, the other member being offset to embrace said arm; a pin removably arranged through said arm member and said ear; an abrader mounted on said pin; a pyrophoric holder having a longitudinal bore-like socket therethrough mounted on the outer end of said offset to overhang said abrader supporting arm; a pyrophoric arranged in said holder to project into the slot in said abrader supporting arm to engage said abrader; a supporting spring for said pyrophoric; and a follower for said spring threaded into the outer end of said holder.

2. A spark producing device comprising a pair of pivoted members, one of said members being provided with a laterally projecting longitudinally slotted abrader supporting arm at its outer end, the other member being offset to embrace said arm and having a holder at its outer end overhanging said arm; an abrader rotatably mounted on said arm; a block of spark producing material arranged in said holder to project through said slot in said arm; and a supporting spring for said block.

3. A spark producing device comprising a pair of pivoted members, one of said members being provided with a laterally projecting longitudinally slotted abrader supporting arm at its outer end, the other member being provided with a holder; an abrader mounted on said arm; a block of spark producing material arranged in said holder and extending through said slot to co-act with said abrader; and handles for said members adapted as stops to limit the opening of the members, one of the handles being removable to permit the holder being swung clear of the abrader supporting arm for the removal or insertion of the block.

4. A spark producing device comprising a pair of pivoted members, one of said members being provided with a laterally projecting longitudinally slotted abrader supporting arm at its outer end, the other member

being offset to embrace said arm and provided with a holder at its outer end; an abrader mounted on said arm; and a block of spark producing material arranged in said holder to project through said slot in said arm.

5. A spark producing device comprising a pair of pivoted members, one of said members being provided with a laterally projecting longitudinally slotted abrader supporting arm at its outer end, the other member being provided with a holder; a cylindrical abrader rotatably mounted on said arm; a block of spark producing material arranged in said holder to project through said slot in said arm into engagement with said abrader, the edges of the slot constituting supports for the block; and a supporting spring for said block.

6. A spark producing device comprising a pair of pivoted members, one of said members being provided with a laterally projecting longitudinally slotted abrader supporting arm at its outer end, the other member being provided with a holder; a block of spark producing material arranged in said holder to project through said slot in said arm into engagement with said abrader, the edges of the slot constituting supports for the block; and a supporting spring for said block.

7. A spark producing device, comprising a pair of pivoted members, one of said members being provided with a laterally projecting longitudinally slotted abrader supporting arm at its outer end, the other member being offset to embrace said arm and having a holder at its outer end overhanging said arm; an abrader rotatably mounted on said arm, a block of spark producing material arranged in said holder to project through said slot in said arm; a supporting spring for said block and an adjusting screw at the top of said holder for regulating the pressure of said block upon said abrader.

In witness whereof, I have hereunto set my hand and seal in the presence of two witnesses.

EDWARD J. MURPHY. [L. S.]

Witnesses:

D. KEMMERER,
J. J. LITTRRELL.
